RAINWEAR

Harold B. Ackerman, Jr., Brooklyn, and Beatrice Cannon Culbertson, New York, N. Y.

Application February 15, 1950, Serial No. 144,236

2 Claims. (Cl. 2—87)

1

The invention relates to improvements in rainwear and has for its objects: first, to provide a convenient and adequate waterproof protective covering for emergencies at such a low cost as to be considered expendable by the average consumer after one or more wearings; second, to provide adjustable features in the neck opening to permit the wearer to accommodate any seasonal clothing; third, to provide adjustable features in the side closings eliminating more expensive conventional closings; fourth, to provide an emergency protective covering that can be packaged small enough to conserve display and counter space and thereby be displayed at convenient locations such as cigar stands, newspaper stands, drug stores and the like, thus being readily available.

Although rainwear has heretofore been designed utilizing inexpensive waterproof materials, the execution of such designs involves such labor that the production costs would be prohibitive for expendable rainwear. And, heretofore, rainwear has been manufactured with stitched or heat-sealed seams in order to provide adequate coverage and employed conventional closings as snaps, ties, hooks and eyes, zippers, buttons, et cetera. We use waterproof material, particularly polyethylene, in such a manner as to eliminate costly seams and yet provide an adjustable neck opening and provide adjustable side closings by use of inexpensive pressure sensitive adhesive tape, thereby eliminating costly factors in both labor and materials.

Figure 1 of the accompanying drawing is a flat view of the invention; Figure 2 is a perspective of the invention; Figure 3 is a fragmentary view showing shoulder closing for the complete protection. This version is most feasible for sheet form of polyethylene. Figure 4 is a flat view of another version of the invention, with the cut depending on the optional use of tubular form of polyethylene which when split, provides wider sheets than standard widths of sheeting. Figure 5 is a front view of this version in use.

In Figures 1, 2, and 3: At the center of the waterproof material 1, is a slit for neck opening 2. At each end of the neck opening 2 are reinforcement tapes 3. Back section 4. Front section 5. The neck opening 2, is adjustable by the optional placement of one single coated adhesive tab, 6. Single coated pressure sensitive adhesive tape tabs, 7, are used for adjustable side closings. Also single coated pressure sensitive adhesive tabs, 8, are placed about three inches to the rear of the neck opening 2, on each side of back section, 4, and by bringing each tab, 8, across the chest as shown in Figure 3, affords more complete coverage for the wearer as well as allowing freedom of arm movement.

In Figures 4 and 5: In waterproof material, 60 1, are slits as shown at 9 and 10. Tapes, 11, are used for reinforcements on slits 9 and 10. These slits 9 and 10 indicated by broken lines,

divide material into upper front sections 12 and 13, back section 14 and front skirt sections 15 and 16, indicated by dotted lines. Adhesive tabs 17 and 18 are placed on side edge of section 16 for adjustable front closing and adhesive tab 19 for adjustable upper front closing. Point 20 is to be placed at the nape of the neck by the wearer, bringing section 12 over the shoulder and across the chest, and then criss crossing with section 13, then fastening section 13 to section 12 securely with tab 19, as shown in Figure 5. As shown in Figure 5, panels 12 and 13 and the upper portion of 14 provide a cape-like effect to the hipline affording freedom of arm movement as well as more complete coverage. Bring front skirt sections 15 and 16 together with section 16 overlapping 15, these are held in place by adhering tabs 17. To hold skirt section in place, tab 18 is adhered to panel 12.

20 We claim:

1. A rain protector comprising a sheet of water repellent material of trapezoidal shape having two parallel and two non-parallel sides, said sheet having a slit therein perpendicular to the shorter side of the two parallel sides of said sheet, said sheet also having a pair of slits therein extending inwardly from both of the non-parallel sides, said slits being parallel to the parallel sides and forming flaps, a pressure sensitive adhesive tape secured adjacent to one of said non-parallel sides near the shorter of said parallel sides and a plurality of pressure sensitive adhesive tapes secured to one of said flaps adjacent to the side of said flap formed by one of said non-parallel sides, a portion of each of said pressure sensitive adhesive tapes extending outwardly from said sheet.

2. A rain protector as claimed in claim 1 wherein said first-mentioned slit extends substantially one-third the distance between said two parallel sides and wherein said second mentioned pair of slits are located a distance from the longer of said two parallel sides approximately equal to one-third the distance between said two parallel sides.
